UNITED STATES PATENT OFFICE.

OTTO B. JOHNSON, OF WILMINGTON, DELAWARE.

CAR-ROOF.

1,151,468.

Specification of Letters Patent. Patented Aug. 24, 1915.

Application filed December 6, 1913. Serial No. 804,994.

To all whom it may concern:

Be it known that I, OTTO B. JOHNSON, a subject of the King of Sweden, having declared my intention of becoming a citizen 5 of the United States, residing in Wilmington, county of Newcastle, State of Delaware, have invented certain Improvements in Car-Roofs, of which the following is a specification.

10 My invention relates to certain improvements in the construction of the roofs of steel passenger cars in which there is a clear story.

One object of my invention is to so construct 15 the roof that the upper section of the carline will be carried down at the sides of the clear story and will be secured to the lower section of the carline.

A further object of the invention is to 20 make the extending portions of the upper section of the carline of a greater width than the main portion thereof, so as to allow for the movement of a window between the inner and outer walls.

25 A still further object of the invention is to extend the upper roof sheet down to the lower roof sheet, forming the outside deck, which is punched and pressed to receive the screen.

30 The invention also relates to details which will be fully described hereinafter.

In the accompanying drawings:—Figure 1, is a transverse sectional view on the line $a-a$, Fig. 3, of a car roof illustrating my 35 invention; Fig. 2, is a transverse sectional view on the line $b-b$, Fig. 3, illustrating my invention; Fig. 3, is a side view of a portion of a car roof made in accordance with my invention; Fig. 4, is a sectional plan view on 40 the line $c-c$, Fig. 3; Fig. 5, is a sectional view on the line $d-d$, Fig. 1; Fig. 6, is a view illustrating a modification; Fig. 7, is an enlarged sectional view of a portion of Fig. 1, showing the detailed method of hanging 45 the clear story window sash; and Fig. 8, is a view illustrating one feature of my invention applied to an ordinary car roof.

50 Referring to the drawings, 1, 1 are the upper section of the roof carlines extending over the clear story of the car and spaced apart as shown.

2, 2 are the lower section of the roof carlines and 3, 3 are the side frames of the car.

55 The upper sections 1, illustrated in Fig. 1, extend in a single piece over the clear story and at each side thereof as indicated at 4,

and these side portions are of a greater width than the roof portions 1. In fact, they are of a width which will allow the car builder to insert a movable window and a 60 screen between the inner and the outer edges of the portions 4, as illustrated in the drawings.

In some instances, the side portions may be made of a separate piece riveted to the 65 roof portion, as indicated in Fig. 6, in which 4^a, 4^a are the separate side pieces and 1^a is the main upper section of the roof carline flanged and bent, as shown, and united at 5^a. In this instance, the flanges of the 70 side sections extend between the flanges of the main roof section. The side members of the upper section of the carlines extend past the lower sections 2 and are riveted thereto at 5, making an exceedingly strong and sub- 75 stantial structure.

The upper roof sheet 6 extends over the top of the upper sections of the carlines and on each side thereof down to the lower roof sheets 7 and overlaps the flange 8 thereof, 80 and the lower roof sheets 7 lap over the side sheets 9. The upper roof sheets are punched to form openings 10 and are pressed at the edges to form flanges 11 to which the screens 12 are attached. The screens extend over 85 the flanges and are secured thereto by wires or other means. The screens, being on the inner side of the roof sheet, are protected to a certain degree.

The construction above described avoids 90 the making and fitting of special screens for the clear story openings.

The casing 21 for the window is applied when the roof is placed in position and takes the same rivets. This construction avoids 95 screws, which are expensive.

The deck web plate forms the inside finish and gives a bond between the upper and lower sections of the carlines, making these important members practically a single element. 100

13 is the ceiling and 14, 14 are the side plates of the clear story which are punched to form the window openings 15. These side plates underlap the upper ceiling, as shown, 105 and the lower sections of the roof plates 16 extend under the lower carlines, and a finish strip 17 is secured at the junction of the side plates 14 and the ceiling. The finish strips 18 are placed at the junction of the ceiling 110 13 and the side plates 14, as shown in Fig. 2. The window sash 19 is secured in the walls

of the opening 15 in any suitable manner, and is preferably hinged so that it can swing either to the open or to the closed position in the usual manner.

5 It will be noticed that the upper sections of the carlines are U-shaped in cross section so that the roof plates 6 can be riveted to the outer flanges of the carlines while the inner side plates 14 can be secured to the inner 10 flanges. This makes a very simple construction.

The side members 4 can be made of any width desired, according to the size of the window opening and the character of the 15 sash to be applied to the opening, and while the upper sections of the carlines and the side members are made in a single piece, as shown in Fig. 1, they may be made in two pieces riveted together, as illustrated in 20 Fig. 6.

I preferably form an opening 20 in the web of the upper carlines, as indicated in the drawings, for the purpose of decreasing the weight without materially weakening 25 the same.

The sill plate 21 of the window casing is inclined toward the center, as shown, and an opening 22 is formed in the outer roof plate to allow for the escape of any water which 30 may accumulate between the screen and the window sash.

It will be noticed that the carlines at the corners 23 are rounded and, consequently, the upper roof sheet can be bent around this 35 corner and extended to the lower roof sheets, as shown, without forming any abrupt angles.

In Fig. 8, I have illustrated my invention 40 as applied to a car roof of the ordinary steel construction. In this instance, the side plates 6^a extend between the upper overhanging carlines and the lower sections of the carlines and have openings 10^a at intervals and flanges surrounding the openings; 45 the flanges being so formed that a screen 12^a can be secured to the flanges. The window casing 21^a is located between the inner and outer plates and this casing has exterior flanges so that it can be secured by 50 bolts or rivets to the said plates.

I claim:—

1. The combination in a car roof, having a clear story, of a series of carlines spaced apart and extending from one side of the 55 car to the other, each carline being made in two sections, the upper section supporting the roof of the clear story and the lower section supporting the main roof, the upper section of the carline being bent at the corners and turned down to form the supports 60 for the side of the clear story and secured to

the inner ends of the lower carline sections, the said side portions being of a greater width than the roof section; roof plates for the clear story extending over the upper 65 carline and down on each side of the side members; and roof plates for the main roof structure.

2. The combination in a car roof having a clear story, of a series of carlines shaped 70 to conform to the roof structure consisting of upper and lower sections; an upper roof sheet extending over the top of the upper section of the carline and on each side thereof; and a lower roof sheet at each side of 75 the car, the joint between the sheets being made at an angle where the lower section of the carline is connected to the side portions of the carline which form the sides of the clear story.

3. The combination in a car roof, of a series of carlines spaced apart and shaped to form the clear story of a car, the upper section of each carline being bent down to 80 form supports for the sides of the clear story, these sections of the carline being of a greater width than the roof portion of the upper section; and a roof sheet extending over the upper section of the carline and down on each side to the lower section and 85 having a series of openings in the sides thereof and having inturned flanges around the openings; an inner plate having openings alining with the openings in the outer plates; and a sash located in the walls of 90 the openings.

4. A roof carline for a car of the clear story type consisting of two lower sections tapered as shown and wider at the base than at the upper end; an upper section extending 100 across the clear story and forming a support for the roof thereof and bent down at each side and connected to the lower sections, the side portions of the upper section being of a greater width than the body of 105 the upper section.

5. An upper section of a carline of a clear story car consisting of a flanged beam curved to conform to the roof of the clear story and turned down at each end to form 110 the supports for the sides of the clear story, said sections being of a greater width at the sides than at the body portion of the said sections.

In testimony whereof, I have signed my 115 name to this specification, in the presence of two subscribing witnesses.

OTTO B. JOHNSON.
